INSECTICIDAL AND FUNGICIDAL SPRAY OIL

Clifford J. Boissonou, Concord, and Wallace J. Yates, Martinez, Calif., assignors to Shell Development Company, San Francisco, Calif., a corporation of Delaware

No Drawing. Application April 27, 1948,
Serial No. 23,614

4 Claims. (Cl. 167—43)

1

This invention relates to insecticidal and fungicidal horticultural spray oil compositions and to aqueous emulsions thereof.

One of the problems of the prior art has been the difficulty of effecting and maintaining proper dispersion of plant-treating agents in spray oil emulsions. The use of many emulsifiers, such as cresols, in petroleum hydrocarbon spray oils has the disadvantage of being effective in emulsifying and removing the protective vegetable wax coatings of plants, thereby causing serious plant injury.

An object of this invention is to provide an emulsifiable spray oil composition capable of effecting and maintaining proper dispersion of an added plant-treating agent in aqueous emulsions thereof. Another object is to provide an emulsifiable hydrocarbon spray oil composition which will not have a deleterious effect on the protective vegetable wax coatings of plants. Other objects will be apparent as the description proceeds.

It has now been discovered that the above and other objects may be attained by a composition comprising a predominant amount of a horticultural hydrocarbon spray oil and a minor but emulsifying and depositing amount therefor of a combination or mixture of an oil-soluble alkyl phenol and certain higher molecular weight open-chain aliphatic carboxylic ester emulsifiers, as hereinafter defined. As one of its functions, the alkyl phenol is a mutual solutizer for the spray oil and said ester.

Described generally, the aforesaid ester emulsifier is a mono-ester of a polyalkylene glycol having from about 14 to about 60 carbon atoms and of a fatty carboxylic acid having from about 12, and preferably from about 16, up to about 30 carbon atoms. Preferably the polyalkylene glycol portion of said ester has from about 14 up to about 30 carbon atoms.

The polyalkylene glycol portion or residue of the emulsifier esters contains recurring alkylene (oxyalkylene) radicals having from two to about six carbon atoms each, inclusive, and it may be a

2

di-, tri-, tetra-, etc., alkylene glycol residue, as for example from octa-ethylene glycol, di-octylene glycol, tri-hexylene glycol, etc.

Various fatty acids may be utilized to supply the acid radical of the esters, but the unsaturated fatty acids are preferable. Thus, preferably at least 20 per cent by weight of the ester or ester mixture is of an unsaturated fatty acid. Illustrative suitable unsaturated fatty acids are: delta-9,10-dodecylene, palmitoleic, oleic, aze-laic, iso-oleic, gadoleic, arachidonic, petroselic, erucic, and cetoleic acids. Particularly effective and outstanding is a mixture of oleate esters of hexaethylene glycol, of octaethylene glycol and of decaethylene glycol containing a predominant proportion of the latter two esters.

The alkyl phenols used in the preparation of the compositions of this invention are oil-soluble substances. They are mutual solutizers for, and co-acting emulsifying, wetting and spreading aids with, the aforesaid ester emulsifiers. They have molecular weights of preferably up to about 250. Other polar groups than the phenolic hydroxyl, such as amino and nitro groups, may also be present in the alkyl phenols. Examples of effective alkyl phenols include the various cresols, thymol, carvacrol, p-octyl and p-butyl phenols, butyl nitro phenols, propyl amino phenols, nitro cyclohexyl phenols, dinitro lower alkylated phenols, etc.

The optimum amount of a given alkyl phenol to be employed in the compositions depends upon various variable factors of a given application. The amount is readily adjusted according to the artisan's skill in the light of the present disclosures. In general, as a guide, from about 0.05 wt. percent to about 0.5 wt. percent of an alkyl phenol, based on the amount of spray oil, is suitable. In most cases from 0.1 wt. percent to 0.3 wt. percent of an alkyl phenol is preferred. Larger or smaller proportions may be used. Further, and as a general guide, the amount of alkyl phenol is selected to range from about one-third to about twice the weight of the ester emulsifier employed.

As to the amount of the ester emulsifier, this amount is generally from about 0.01% to about 5%, preferably from about 0.05% to about 2%, by volume of the oil present in the spray oil composition. The best amount for a given application depends upon the particular ester employed, and also upon other factors familiar to persons skilled in this art. As illustrative, some preferred amounts of the ester emulsifier have been found to be from about 0.1% to about 1% by volume of the spray oil present.

5 10

time of each insecticidal emulsion in the spray machine of 30 seconds; spray nozzle orifice diameter of $5/64$ inch; distance of nozzle to target of orange tree leaves of six feet; and spraying time of 6 seconds. When calculated on the basis of a hundred gallons of finished emulsion, there was employed for each emulsion two ounces of a water-conditioner or water-soluble spreader made up of the commonly used conventional twenty weight per cent casein with eighty weight per cent sodium carbonate.

¹ A mixture of mono-oleate esters of hexaethylene glycol, of octaethylene glycol, and of decaethylene glycol in which the latter two predominate.

The present horticultural spray base oils include those known to the art for use in spray oil emulsions. They are usually substantially free from unsaturated and aromatic hydrocarbons known to be injurious to plant tissues. Summer spray oils usually have viscosities ranging from about 40 to about 300 seconds Saybolt at 100° F. Dormant winter spray oils usually have viscosities ranging from about 70 to about 300 seconds Saybolt at 100° F. and have from about 50% to about 95% unsulfonatable residue, low sulfonatable residue type of mineral spray oils being preferred.

The present emulsifiable compositions may have incorporated therewith, either when alone or in aqueous emulsion, an effective quantity of a solid horticultural plant-treating substance, such as plant-growth promoters, plant deficiency correctives, fungicides and insecticides.

An example of a formulation of the present for summer use is as follows:

Emulsifiable Spray Oil Components	Weight Per Cent
A technical white summer spray oil.....	99.6
Cresols.....	0.2
Octaethylene glycol mono-oleate.....	0.2
Trace of water.....	.....
Total Weight Per Cent.....	100.0

In general, each gallon of the spray oil composition is used, emulsified in from about 50 to about 2000 gallons of water, with or without the incorporation of other materials, including water-soluble spreaders, as are well understood in the art.

Comparative oil spread and oil deposit tests on orange tree leaves by a standardized procedure were made with spray oil emulsions with and without the present emulsifier combinations, and with other emulsifier combinations, the results of which are given in Table I. Conditions used for these spraying tests were: oil concentration of 1.67% by volume of water used (5 volumes oil to 300 volumes water); water hardness in parts per million (P. P. M.) of calcium carbonate was 150; water temperature of 75° F.; pressure in spray machine of 500 lbs. per sq. inch gage; circulation

30 35 40 45 50 55 60 65 70 75

in an orchard test of the present invention, valencia orange trees were sprayed with an aqueous emulsion (water continuous phase) of an illustrative composition of this invention composed of a light medium mineral spray oil having a Saybolt universal viscosity of 70 seconds at 100° F. and a 92% unsulfonatable residue, and containing 0.5% by vol. (based on the oil) of mono-oleate esters of a polyethylene glycol, which glycol had from about seven to about twelve ethylene glycol units (i. e. oxyethylene units) therein, and 0.3% by vol. (based on the oil) of cresols. The results from these orchard trials were found to be: emulsification was excellent and the observed oil deposit and oil spread on orange tree foliage in the orchard was excellent. Subsequent inspection for insecticide control showed that excellent control of red scale was obtained; there was no serious injury to the thus-sprayed orange tree foliage.

Proper dispersion of an added toxic agent, and of the spray oil, generally termed compatibility, in emulsions prepared in accordance with the invention, is shown by illustrative embodiments thereof as described hereinafter. An ester emulsifier of the invention was obtained by esterification condensation of stoichiometric molal quantities of high molecular weight fatty mono-carboxylic acids, including at least about twenty per cent by weight of oleic acid, with a mixture of hexaethylene glycol, octaethylene glycol and decaethylene glycol. The fatty acids and the polyalkylene glycols may be heated together thereby driving off water with or without the use of a catalyst in methods well known to the art. The resultant mixture of fatty acid mono-esters of said polyethylene glycols, termed agent B, was tested for compatibility and compared under comparable conditions with a representative prior art emulsifier, agent C. The tests were made under the same operating conditions as described hereinbefore with reference to the other tests. Agent C was a mixture of 0.75 part of saturated cocoanut fatty acid mono-esters of tri-, tetra-, and penta-ethylene glycols, 0.25 part of diocetyl sodium sulfo-succinate, 1.67 parts of sodium petroleum mahogany sulfonates and 3.33 parts of cottonseed oil. Other details and the results are given in Table II.

TABLE II

Compatibility of medium spray oil formulations with sodium fluoaluminate and zinc oxide

Materials Added to Spray Oil, Per Cent by Vol.						
Agent B of invention	0.25		0.25		0.25	
Cresols	0.25		0.25		0.25	
Comparative Agent C	0.6		0.6		0.6	
Plant-Treating Agents in Lbs. Per 100 Gals. of Finished Oil-In-Water Spray:						
Sodium Fluoaluminate	1	1	1	1	1	1
Zinc Oxide						
Water Conditioner in Ounces Per 100 Gals. of Finished Oil-In-Water Spray: Bentonite			4	4		
Results on Compatibility upon Emulsification:						
Free Oil	Medium amount	None	Extreme	None	Moderate	None
Flocculation	Extreme	Very slight	Medium amount	Medium amount	Extreme	Very slight
Scumming	Medium amount	None	None	None	Moderate	None
Sticking to Tank	Slight	do	do	do	None	Do

From the data in Table II, it is seen that the use of agent B of this invention provided superior results in at least one or more of the important criteria of compatibility over results obtained with agent C. Agent B substantially eliminated extreme, i. e. excessive and impractical flocculation of the added plant-treating agents, and also eliminated excessive separation of free oil from the emulsion.

Similar compatibility tests were also conducted with basic copper sulfate, and also with Bordeaux mixture. Details and results are summarized in Table III.

phenol, said ester having between about 14 and 20 about 30 carbon atoms in the glycol portion and between about 16 and about 30 carbon atoms in the acid portion.

3. A water-emulsifiable insecticidal spray oil composition comprising a predominant amount of 25 a horticultural hydrocarbon spray oil having dissolved therein between about 0.01% and about 5% by volume of a fatty acid monoester of a polyalkylene glycol and a solubilizing amount of an oil-soluble unsubstituted alkyl phenol, said 30 ester having between about 14 and about 60 carbon atoms in the glycol portion and between about

TABLE III

Compatibility of heavy dormant spray oil formulations with copper compounds

Materials Added to Spray Oil, Per Cent by Volume of the Oil:

Cresols		0.4		0.4	
Agent D ¹	0.85		0.85		
Added Toxic Agent Per 100 Gals. of Finished Oil-In-Water Spray:					
Basic Copper Sulfate (lbs.) ²	6	6			
Bordeaux mixture (lbs.) ³			16	16	
Results on Compatibility upon Emulsification:					
Free Oil	None	None	None	None	None
Flocculation	Extreme ⁴	do	Extreme ⁴	do	do
Scumming	Slight	do	None	do	do
Sticking to Tank	do	do	Slight	do	do

¹ Agent D was a mixture of 3 parts of saturated cocoanut fatty acid mono-esters of tri-, tetra-, and penta-ethylene glycols and 1 part of diethyl sodium sulfo-succinate.

² Contains 55% of copper.

³ Containing 22% of copper.

⁴ Flocculate precipitate was the size of bird-shot, excessive and unsatisfactory.

In addition to the compatibilities with toxic agents noted above, other tests have shown that the present compositions also have excellent compatibility with DDT powders and similar organic toxicants in emulsion form and with lime-sulfur mixtures.

We claim as our invention:

1. A water-emulsifiable insecticidal spray oil composition comprising a predominant amount of a light medium mineral spray oil having a Saybolt universal viscosity of about 70 seconds at 100° F. and having an unsulfonatable residue of about 92%, said oil having dissolved therein about 0.5% by volume of monooleate esters of a polyethylene glycol having from about 7 to about 12 oxyethylene units, said esters being solubilized in said oil by about 0.3% by volume of oil-soluble unsubstituted cresols.

2. A water-emulsifiable insecticidal spray oil composition comprising a predominant amount of a horticultural hydrocarbon spray oil having dissolved therein between about 0.05% and about 2% by volume of an unsaturated fatty acid mono-ester of a polyalkylene glycol and a solubilizing amount of an oil-soluble unsubstituted alkyl phenol,

12 and about 30 carbon atoms in the acid portion.

4. A water-emulsifiable spray oil composition comprising a predominant amount of a horticultural hydrocarbon spray oil having dissolved therein between about 0.01% and about 5% by volume of a monooleate ester of a polyethylene glycol, and a solubilizing amount of oil-soluble unsubstituted cresols, said ester having from about 7 to about 12 oxyethylene units in the glycol portion thereof.
